UNITED STATES PATENT OFFICE.

ELIZABETH M. CARHART, OF JEWELL, VIRGINIA.

CLOSURE MEANS FOR BOTTLES.

Application filed April 6, 1926. Serial No. 100,147.

This invention relates to closure members for receptacles and particularly to those closures intended for closing the openings of bottles such as beverage bottles, ketchup bottles etc.

The closure members commonly used for closing beverage bottles have certain disadvantages in that it is necessary to have a particular kind of tool to remove them.

10 The primary object of my invention is the provision of an improved closure member or cap for bottles and the like.

Another object of my invention is the provision of improved closure members for bottles which will not only be removable by the use of any long slender instrument or from a nail in a wall, but will also have means for causing the release of the closure member with the application of less force than 20 is usual for the performance of such an operation.

Other and further objects of my invention will be apparent, to those skilled in the art, from a reading of the complete specification.

25 Referring to the drawing wherein I have illustrated an embodiment of my invention,

Fig. 1 is an enlarged elevation of my invention applied to the mouth of a bottle.

Fig. 2 is a top plan view of the invention 30 shown in Fig. 1.

Fig. 3 is a cross section on the line 3—3 of Fig. 1.

Fig. 4 is a cross section at 90° from that of Fig. 3 as indicated in line 4—4, Fig. 2 35 but showing the closure member being removed from the bottle by one method.

The same reference characters refer to the same or similar parts throughout the several views of the drawing.

40 The bottle, to which my invention is illustrated as being attached, is designated by the numeral 10. The body portion of my closure member I have designated by the numeral 11. The general outline of this 45 closure member is similar to the closure member commonly used for beverage bottles, it having a crimped flange 12 and a cork or similar lining 13 to act as a sealing member. As in the structure commonly used for closing beverage and similar bottles, the crimped edge 12 is caused to bind in the groove 14, to firmly press the cork or similar sealing member 13 against the upper edge of the bottle.

50 55 In order to provide a means for easily removing the closure member, I provide an

elongated metallic loop as a wire 15, the bight being outside of the closure member as shown in Figs. 1, 2 and 4. The ends of the loop extend under the crimped edge 60 of the closure member 12 and pass up over the top of the sealing member 13 and down on the opposite edge to be suitably secured to the crimped edge. A suitable method of securing the ends is illustrated, wherein the 65 ends are bent around on the outside of the crimped edge 12 as shown in Figs. 1 and 4 at 16.

In order to provide a space for the wire 15, I have provided two grooves 17 formed 70 by struck-up portions 18 which extend across the top 11 of the body portion of the closure member. The depth of the groove is made equal to the diameter of the wire.

The action in applying the closure member to a bottle to close and seal the same is similar to the action of the closure cap in common use except that the opening wire 15 is in place as shown in Fig. 1 before the cap is applied. When applied, the crimped edge is forced inwardly, by any well known or suitable appliance, to be held by the wall of the groove 14, thus forcing the sealing cork 13 against the top rim of the bottle to seal the contents of the bottle from the outside air.

When it is desired to open the bottle, any instrument as a key or nail may be inserted in the loop 15 as illustrated in Fig. 4 at 19 and the outer end lifted, with the inner end 90 on the side of the closure member opposite to the loop. This lifting action has a double effect upon the closure member. In the first place, there is an upward lift on the edge of the closure member, due to the lever action 95 of the key on the loop. In addition to this straight lever action, there is another action which takes place on the principle of a pulley, the wire loop acting as the rope or cable and the edge of the crimped portion as the 100 pulley. This is illustrated in Fig. 4. This pulley and cable action forces the cap and bottle apart and separates the sealing member 13 from the main body of the closure member as illustrated in Fig. 4.

105 The action of the wire in separating the closure member from the bottle or other container necessitates only about half the usual effort as is required to remove the closure member in the structure in common use.

110 While I have described and shown one form of my invention, I desire to have it

understood that I do not limit myself to the exact showing and that modifications and changes may be made without departing from the spirit of my invention and within the scope of the appended claims.

Having described my invention, what I claim is:—

1. A closure device for bottles and the like, comprising a body portion having a top, a flange, a sealing member, a flexible elongated member in the form of a loop extending across and free of the body portion between the top and the sealing member, the ends being secured at one side of the top adjacent the flange, the bight of the loop extending beyond and from the flange, the flange being of sufficient rigidity to permit of the loop to raise the cap from the top of the container, the loop sliding on the contacting edge of the cover member flange and coacting by pressure on the top of the container to raise the cap when the loop is lifted.

2. A closure device for bottles and the like, comprising a body portion having a top, a flange, a sealing member, a flexible elongated member in the form of a loop extending across and free of the body portion between the top and the sealing member, the ends being bent up around the edge of the flange, the bight of the loop extending beyond and from the flange, the flange being of sufficient rigidity to permit of the loop to raise the cap from the top of the container, the loop sliding on the contacting edge of the cover member flange and coacting by pressure on the top of the container to raise the cap when the loop is lifted.

3. A closure device for bottles and the like, comprising a body portion having a top, a flange, a sealing member, a flexible elongated member in the form of a loop extending across and free of the body portion between the top and the sealing member, the ends being secured at one side of the top adjacent the flange, the bight of the loop extending beyond and from the flange, the top being grooved thereacross, to receive the portion of the loop extending across the top, the flange being of sufficient rigidity to permit of the loop to raise the cap from the top of the container, the loop sliding on the contacting edge of the cover member flange and coacting by pressure on the top of the container to raise the cap when the loop is lifted.

4. A closure device for bottles and the like, comprising a body portion having a top, a flange, a sealing member, a flexible elongated member in the form of a loop extending across and free of the body portion between the top and the sealing member, the ends being bent up around the edge of the flange, the bight of the loop extending beyond and from the flange, the top having a pair of grooves thereacross, to receive the portion of the loop extending across the top, the flange being of sufficient rigidity to permit of the loop to raise the cap from the top of the container, the loop sliding on the contacting edge of the cover member flange and coacting by pressure on the top of the container to raise the cap when the loop is lifted.

In testimony whereof I hereunto affix my signature,

ELIZABETH M. CARHART.
